(57) **CLAIM**

The ornamental design for an automotive vehicle exterior.

DESCRIPTION

FIG. 1 is left side, front, top perspective view showing my new design;

FIG. 2 is a left side, rear, top perspective view thereof;

FIG. 3 is a front view thereof; and

FIG. 4 is a rear view thereof.

FIG. 5 is a right side elevation view thereof;

FIG. 6 is a left side elevation view thereof; and,

FIG. 7 is a top plan view thereof.

The invention is shown together with environmental structure in dashed lines in FIGS. 1-7, the environmental structure forming no part of the claimed design.

The broken lines shown throughout the drawing views are for illustrative purposes only and form no part of the claimed design.

1 Claim, 7 Drawing Sheets
